(57) **CLAIM**

The ornamental design for a cover for a starter battery, or the like, as shown and described.

DESCRIPTION

FIG. 1 is an isometric view of a cover for a starter battery or the like showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof.

FIG. 8 is an isometric view of an alternative embodiment of the invented cover for a starter battery;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines shown represent environmental structure only and form no part of the claimed design.

1 Claim, 8 Drawing Sheets
